(57) **CLAIM**

The ornamental design for a fuel tank as shown and described.

DESCRIPTION

The patent or application file contains at least one drawing executed in color. Copies of this patent or patent application publication with color drawing(s) will be provided by the Office upon request and payment of the necessary fee.

FIG. 1 is a top-front-right side perspective view of a fuel tank embodying my new design;

FIG. 2 is a top-front perspective view thereof;

FIG. 3 is a front-left side perspective view thereof;

FIG. 4 is a top-front-left-side perspective view thereof;

FIG. 5 is a top-left side perspective view thereof;

FIG. 6 is a top-rear-left side perspective view thereof;

FIG. 7 is a top-rear perspective view thereof;

FIG. 8 is an rear-right side perspective view thereof;

FIG. 9 is a top-rear-right side perspective view thereof;

FIG. 10 is a top-right side perspective view thereof;

FIG. 11 is a bottom-front-right side perspective view thereof;

FIG. 12 is a front-right side perspective view thereof;

FIG. 13 is a front-left side perspective view thereof;

FIG. 14 is a bottom-front-left side perspective view thereof;

FIG. 15 is a bottom-left side perspective view thereof;

FIG. 16 is a bottom-rear-left side perspective view thereof;

FIG. 17 is a bottom-rear perspective view thereof;

FIG. 18 is an bottom-rear-right side perspective view thereof;

FIG. 19 is a bottom-rear-right side perspective view thereof;

FIG. 20 is a bottom-right side perspective view thereof;

FIG. 21 is a front elevation view thereof;

FIG. 22 is a rear elevation view thereof;

FIG. 23 is a left side elevation view thereof;

FIG. 24 is a right side elevation view thereof;

FIG. 25 is a top plan view thereof; and,

FIG. 26 is a bottom plan view thereof.
